STOCKING POCKET

Clara D. Strieby, Bloomington, Ill.

Application December 3, 1935, Serial No. 52,693

1 Claim. (Cl. 2—239)

This invention relates to the class of wearing apparel and pertains particularly to the provision of pockets in articles of clothing.

The primary object of the present invention is 5 to provide a stocking with a pocket of novel construction whereby small valuable articles may be safely carried upon the person.

The invention broadly contemplates the provision of a stocking having a reinforced top to which 10 is attached a body of fabric which forms one wall of a pocket of which the stocking top forms the opposed wall. Joined with the stocking top over the fabric body is one portion of a two-part fastening device of the character generally known as 15 a "Zipper" fastener, while the other portion of the device is secured to the fabric body and by this means the free top edge of the fabric body may be joined throughout its length with the stocking top so as to effectively prevent the escape 20 of any articles disposed in the pocket which the fabric body forms with the stocking.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark 30 no material departure from the salient features of the invention as expressed in the appended claim.

In the drawing:—

Figure 1 is a view showing a stocking with the 35 pocket embodying the present invention applied thereto.

Fig. 2 is an enlarged view in elevation of the upper part of a stocking top showing the pocket partially open.

Fig. 3 is a sectional view taken on the line 3—3 of Fig. 2.

Referring now more particularly to the drawing, the numeral 1 indicates generally a stocking in which the top portion is formed of a double thickness 45 of material, as indicated generally by the numeral 2 whereby added weight and strength is given to this portion.

The present invention comprises the attach-

ment to the face of the double thick portion 2 of the stocking of a body of fabric 3 which may be of any desired outline or contour but which is here illustrated as being of rectangular outline and stitched to the portion 2 of the stocking along 5 one longitudinal and two transverse edges, as indicated at 4, the stitching being in the form of a seam whereby the stitching is concealed. The stitching along the transverse edges of the fabric body 3 extends only half-way across the width of 10 the body so that there is provided a free or flap portion 5 which is turned in between the stocking top and the outside of the fabric body.

The numerals 6 and 7 indicate tapes forming the two portions of a fastening device of the type 15 known as a "Zipper" fastener, and the tape 6 has one longitudinal edge stitched along the free top edge of the fabric body 3, as indicated at 8, while the tape 7 has one longitudinal edge and its two end edges stitched to the portion 2 of the stocking 20 above the tape 6 so that the two tapes will have the interconnecting metal elements 9 which are carried thereby in proper relation to be joined together by the fastening device 10 when the latter is drawn across the top of the pocket between 25 the opposed edges of the tapes. The tape 6 also has its end edges stitched to the stocking top, and thus it will be apparent that when the fastener 10 is drawn in the proper direction so as to interconnect the metal elements 9, the area between 30 the fabric body 3 and the stocking top will be completely closed and any valuables disposed in the pocket will be safely retained.

I claim:

In a stocking having a heavy top, a pocket upon 35 said top comprising a body of fabric stitched to the top and having one edge free therefrom, a fabric strip stitched to the top along one longitudinal edge and having the other longitudinal edge free and opposing the said fabric body free 40 edge, and fastening elements disposed throughout the said opposed free edges and adapted to be interconnected to join said edges throughout their length, said fabric body having an integral extension along said free edge, which is turned in 45 between the body and stocking top.

CLARA D. STRIEBY.
